UNITED STATES PATENT OFFICE.

THOMAS H. BELL AND JOHN G. SCHOENLEBER, OF NEW YORK, N. Y.

CLEANING APPARATUS.

Application filed March 20, 1920. Serial No. 367,356. Renewed September 19, 1922. Serial No. 589,286.

To all whom it may concern:

Be it known that we, THOMAS H. BELL and JOHN G. SCHOENLEBER, citizens of the United States, residing at New York, in the county of New York and State of New York, have invented certain new and useful Improvements in a Cleaning Apparatus, of which the following is a specification.

Our invention relates to cleaning apparatus and the main object is to provide an improved article capable of use selectively as an ordinary carpet sweeper or as a vacuum cleaner.

We aim also to provide a sweeper structure having an electric motor mounted thereon to drive a fan or suction member at desired times for the selective operation aforesaid.

In addition, we aim to provide a novel improved and simplified construction as hereinafter described in connection with accompanying drawings of one preferred embodiment wherein:

Figure 1 is an elevational view of the apparatus;

Figure 2 is a plan view with the handle and suction apparatus removed;

Figure 3 is a fragmentary side elevation;

Figure 4 is a partial transverse sectional view;

Figures 5 and 6 are respectively plan and side elevational views of the fan or suction member employed, and

Figure 7 is a plan view of the suction chamber.

Referring specifically to the drawings wherein like reference characters designate like or corresponding parts, A is a hollow housing of any suitable material, for instance wood, and of any desired shape or size having a dust-entrance opening 8 in the bottom. Disposed in opening 8 is a rotary brush or dust-dislodging member 9 having a shaft 10 journaled in the ends of the housing and exteriorly of the same having friction wheels 11 keyed thereto. The bristles of the brush extend below the housing to engage the carpet or floor surface and wheels 12 may be suitably journaled on axles 13 secured to the housing ends. Certain wheels 12 may contact with wheel 11 so as to turn the brush through traveling of the wheels 12 as shown in Figure 3.

Secured to the top of the housing is a hollow suction chamber or casing B, preferably of metal, being secured in any suit-

able manner as by means of bolts or the like 13' passing through said top and the bottom wall of the casing. A dust passageway or opening 14 is provided centrally in the top 60 of the housing and registers with a similar opening 15 in the bottom wall of the casing, having a marginal reinforcing flange 16 thereat. The dust escapes from the casing through an outlet 17 into a suitably constructed collecting bag 18 fastened therein and at its free end supported in any desired way from a draft pole or handle 19 fastened rigidly to a bail 20 of U-shape having its arms pivoted to the housing at 21 for vertical movement.

Within the housing a fan or suction member C is disposed for rotary movement. This fan may be of any desired construction but is preferably made like Figures 3 75 and 4. It may be stamped from flat steel to have a marginal reinforcing flange 22, a hub tube 23 and a plurality of air-impinging blades 24 struck out from the sheet to provide relatively large openings 25 so that 80 a greater suction can be obtained. These blades are preferably curved transversely as shown with certain ends cut away as at 26. A power shaft 27 is engaged by the sleeve 23 and set screw 28 passes through the sleeve 85 and engages the shaft to mount the fan thereon, a suitable opening 29 being provided in the casing to enable free movement of the parts. This shaft 27 is preferably the main shaft of a suitable electric motor 30 90 mounted by a housing 31 bolted at 32, through a flange 33 to the top of casing B. The current for this motor may be supplied through feed wires 34 to a suitable switch 35, mounted on the handle 19 and from 95 thence through wires 36 to terminals of the motor at 37.

In use, with switch 35 "off", the apparatus may be manually propelled or pushed over the surface to be cleaned so that wheels 100 11 and 12 will operate the brush and the brush bristles will dislodge and sweep the dust and dirt in the same manner as an ordinary carpet sweeper or broom. However, when desired, switch 35 may be 105 "closed", thus energizing the motor 30 resulting in rotating the fan or suction member C so that the dust and dirt, by the vacuum created will be drawn or sucked into the housing A through opening 8, 110 through openings 14 and 15 into casing B and thence into the collecting bag or sack

through outlet 17. The form of fan employed will offer little resistance to the air and a maximum suction may be obtained.

Since merely the preferred embodiment 5 has been illustrated and described, it is to be understood that changes in the details of construction may be resorted to within the spirit and scope as defined by appended claim.

10 We claim—

In a suction fan, the combination with a casing having an inlet opening in one side and a discharge opening in a plane transverse to the direction of the inlet and an

opening in the side opposite the inlet, of an 15 impeller which consists of a plate rotating within the casing and provided with transversely curved vanes projecting toward the inlet and with a series of relatively large 20 openings each of which is adjacent the concave side of a vane, whereby a communication is maintained between the suction side of the impeller and the last mentioned opening in the casing.

In testimony whereof we have affixed our 25 signatures.

THOMAS H. BELL.
JOHN G. SCHOENLEBER.
